Ralph Koenig ATTORNEY

UNITED STATES PATENT OFFICE.

EDGAR MILLNER, OF ST. LOUIS, MISSOURI.

HEATER FOR GASOLENE-SUPPLY PIPES.

1,399,393.

Specification of Letters Patent.

Patented Dec. 6, 1921.

Application filed July 30, 1920. Serial No. 400,021.

To all whom it may concern:

Be it known that I, EDGAR MILLNER, a citizen of the United States, residing at St. Louis, Missouri, have invented a certain new and useful Improvement in Heaters for Gasolene-Supply Pipes, of which the following is a specification, reference being had to the accompanying drawing, forming a part thereof.

10 This invention relates generally to heating devices and, more particularly, to a certain new and useful heating attachment for the tube or pipe that leads from a gasolene or other hydro-carbon supply tank or reservoir to a carbureter or other vaporizing device, or to a burner, and the like.

It is generally known that in the operation of internal combustion engines, and particularly during the colder months of the year, the carbureter does not always function properly, due to the fact that the gasolene delivered to it is comparatively cold and, therefore, will not vaporize readily; and it is one of the principal objects of my invention to provide relatively simple and efficient means for materially increasing the temperature of the gasolene, preferably at a point in the supply pipe closely adjacent to the carbureter, thereby facilitating and insuring more perfect vaporization of the gasolene, or like volatile fluid, as it enters and passes through the carbureter.

With the foregoing and other objects in view, my invention consists in certain novel features of form, construction, arrangement, and combination of parts hereinafter more fully described and claimed and illustrated in the accompanying drawing, in which—

40 Figure 1 is a vertical section taken lengthwise through the center of a heating device embodying my invention;

Fig. 2 is a cross-section taken approximately on the line 2—2 of Fig. 1; and

45 Fig. 3 is a cross section taken approximately on the line 3—3 of Fig. 1.

Referring by numerals to the accompanying drawing, which illustrates a practical embodiment of my invention, 10 designates the gasolene supply pipe or tube that leads 50 from the gasolene-supply tank or reservoir to the carbureter, and my improved heating device is especially adapted for attachment upon this pipe, preferably at a point closely adjacent to the carbureter.

55 It is to be understood that, while my new heating device is particularly adapted for

use, and is herein shown and will be described in connection, with the gasolene-supply pipe of an internal combustion engine, it may be equally well used in connection with other hydro-carbon supply pipes leading to burners and the like.

My improved heating device as shown includes a substantially tubular body 11, preferably formed of flexible material, such as 65 fabric or a combination of fabric and rubber, or the like; and secured in any suitable manner to the ends of this tubular body are heads 12 and 13, preferably formed of suitable insulating material, such as fiber.

70 The heads 12 and 13 are provided with centrally arranged apertures 14 and 15, respectively, for the accommodation of the supply-pipe 10; and seated in the head 13, which is substantially longer than the head 75 12, is a set-screw 16, which provides means for securing the heating device in position upon the gasolene-supply pipe.

75 The tubular body 11 is somewhat greater in diameter than the supply pipe 10, in order 80 to form or provide a heating chamber 17, of suitable area, around that portion of the supply pipe 10 inclosed or embraced between the heads 12 and 13; and arranged within this heating chamber 17 and extending 85 from head 12 to head 13 is a tubular member 18 of relatively thin and suitably flexible sheet asbestos or other analogous material, which serves as a support for the heating element, the latter being in the form 90 of a resistance coil 19. This coil encircles the tubular member 18 and occupies the relatively narrow annular space between the tube or shell 18 and the tubular body 11, the terminal portions 20 of the resistance coil 95 19 extending into small metal tubes 21 that are seated in head 13. These terminal portions of the coil are firmly secured in the tubular members 21 by means of set-screws 100 or the like 22, the same being screw-seated in the head 13, and their inner ends bearing against the terminal portions 20 within tubular members 21.

105 The electric current for heating the resistance coil may be obtained from any suitable source of supply, as, for instance, by means of conductors 23, which lead from a battery 24 to the outer ends of tubular members 21, said conductors being secured in said tubular members 21 by suitable set- 110 screws 25.

To maintain the tubular member or shell

18 in suitably distended and in spaced relation throughout from the embraced pipe, and also provide a firm and substantial support for the resistance coil, suitable spacing rings or washers, such as 26, are arranged upon the supply pipe 10 within chamber 17 and the outer edges of said spacing members bearing directly against the inner surface of the tubular member 10 or shell 18.

When in service, the electric current from battery 24, or other source of supply, passes through resistance coil 19, thereby heating the same, and in a very short time the air 15 within chamber 17 will be heated, with the result that the gasoline passing through pipe 10, and which latter passes through heating chamber 17, will be pre-heated just prior to its delivery to the carburetor.

20 It will be understood that my improved heating device is not intended to heat the gasoline in the supply pipe to such a degree as to effect vaporization, but, on the other hand, the gasoline passing to the carburetor will be heated to such a degree as will insure its rapid vaporization while passing through the carburetor, and which result is highly desirable, particularly during relatively low atmospheric temperatures.

25 Obviously, a suitable electrical switch can be located on either one of the conductors 23, thus forming a heating device to be turned on or off at the will of the operator.

30 A gasoline heating device of my improved construction is comparatively simple, is 35 capable of being easily and cheaply produced, can be readily installed, is economical in point of current consumption, and is very effective in performing its intended 40 functions.

45 It will be readily understood that minor changes in the size, form and construction of the various parts of my improved heating device may be made and substituted for those herein shown and described without departing from the spirit of my invention, the scope of which is set forth in the appended claims.

Having thus described my invention, what 50 I claim and desire to secure by Letters Patent is:

1. A heating device or hydro-carbon supply pipes comprising, in combination, a pair of spaced heads adapted for location upon a supply pipe, a flexible tube arranged between, and having engagement with, the heads, a shell disposed within the tubular member and adapted to provide a chamber around the pipe to be heated, and an electric 55 heating coil for heating the chamber and pipe, the coil being disposed between the shell and tubular member.

2. A hydro-carbon supply pipe heating device comprising, in combination, a pair of spaced heads adapted for location upon a

60 supply pipe, a flexible tubular member disposed between, and having engagement with, the heads, a tubular coil-supporting member arranged within the flexible tubular member, and a resistance coil on the 70 tubular supporting member.

3. A hydro-carbon supply pipe heating device comprising, in combination, a pair of spaced heads adapted for location upon a supply pipe, a flexible insulation tube disposed between and connected to the heads, a tubular coil-supporting shell disposed within the tube, and resistance wire coiled between the shell and tube and having its terminals extending into one of the heads. 80

4. A hydro-carbon supply pipe heating device comprising, in combination, a pair of spaced heads adapted for location upon a supply pipe, one of which heads is of insulation material, a flexible insulation tube 85 disposed between and fixed to the heads, a tubular coil-supporting shell disposed within the tube and adapted to provide a chamber around the pipe to be heated, and resistance wire coiled between the shell and tube and having both its ends extending 90 into the insulation head.

5. A hydro-carbon supply pipe heating device comprising, in combination, a pair of spaced heads adapted for location upon a supply pipe, one of which heads is of insulation material, a flexible insulation tube disposed between and fixed at its ends to the heads, a tubular shell disposed within the tube and having engagement at its 100 ends with the heads, the shell with the heads providing a substantially closed chamber around the pipe to be heated, and a resistance wire coiled between the shell and tube and having both its ends extending into the 105 insulation head for electrical connection with a source of supply.

6. A hydro-carbon supply pipe heating device comprising, in combination, a pair of spaced heads adapted for location upon a supply pipe, one of which heads is of insulation material, a flexible insulation tube disposed between and fixed at its ends to the heads, a tubular shell disposed within the tube and having engagement at its 110 ends with the heads, the shell with the heads providing a substantially closed chamber around the pipe to be heated, a resistance wire coiled between the shell and tube and having both its ends extending into the 115 insulation head for electrical connection with a source of supply, and pipe spacing rings disposed within the shell.

7. The combination with a hydro-carbon supply pipe, of a tubular member disposed upon and inclosing a portion of the pipe, heads disposed upon and closing the ends of the tubular member, a shell disposed within the tubular member, the shell being spaced from, and providing a chamber 120

125

130

around, the pipe, and an electric heating coil for heating the chamber and pipe, the coil being disposed between the shell and tubular member.

- 5 8. The combination with a hydro-carbon supply pipe, of a flexible tubular member disposed upon and inclosing a portion of the pipe, heads disposed upon and closing the ends of the tubular member, a shell disposed within the tubular member and having engagement at its ends with the heads, and an electric heating coil for heating the pipe, the coil being disposed between the shell and tubular member.
- 10 9. The combination with a hydro-carbon supply pipe and a source of current supply, of a tubular member disposed upon and in-

closing a portion of the pipe, heads disposed upon and closing the ends of the tubular member, one of the heads being of insulation material, a shell disposed within the tubular member and spaced from the pipe, the shell having engagement at its ends with the heads and with the heads providing a substantially closed chamber around the pipe, and an electric heating coil for heating the chamber and pipe, the coil being disposed between the shell and tubular member and having both its ends extending into the insulation head for electrical connection with the source of supply.

In testimony whereof, I have signed my name to this specification.

EDGAR MILLNER.

It is hereby certified that in Letters Patent No. 1,399,393, granted December 6, 1921, upon the application of Edgar Millner, of St. Louis, Missouri, for an improvement in "Heaters for Gasolene-Supply Pipes," an error appears in the printed specification requiring correction as follows: Page 2, line 52, claim 1, for the word "or" read *for*; and that the said Letters Patent should be read with this correction therein that the same may conform to the record of the case in the Patent Office.

Signed and sealed this 31st day of January, A. D., 1922.

[SEAL.]

WM. A. KINNAN,

Acting Commissioner of Patents.
